[57] CLAIM

The ornamental design for a travel case for a nested pair of breast size and shape enhancing forms, as shown and described.

DESCRIPTION

FIG. 1 is a front elevational view of a travel case for a nested pair of breast size and shape enhancing forms showing my new design in a closed condition;

FIG. 2 is a rear elevational view thereof;

FIG. 3 is a left side elevational view thereof, the right side being a mirror image thereof;

FIG. 4 is a top plan view thereof; and

FIG. 5 is a bottom plan view thereof;

FIG. 6 is a perspective view thereof in an open condition; and,

FIG. 7 is a front elevational view thereof in an open condition.
